CLAIM

The ornamental design for a tamper-resistant cap seal for drum-type containers, as shown and described.

DESCRIPTION

FIG. 1 is a perspective view of the underside of a tamper-resistant cap seal for drum-type containers showing our new design;

FIG. 2 is a perspective view showing the top thereof;

FIG. 3 is a fragmentary sectional view thereof taken on plane 3—3 in FIG. 2, showing the angle of the inwardly bent tabs;

FIG. 4 is a top plan view thereof; and,

FIG. 5 is a bottom plan view thereof.
